UNITED STATES PATENT OFFICE.

WALTER PEARSON AND EDWIN P. QUATTLEBAUM, OF MOBILE, ALABAMA.

LOCOMOTIVE ASH-PAN.

1,173,855.

Specification of Letters Patent. Patented Feb. 29, 1916.

Application filed October 21, 1915. Serial No. 57,107.

To all whom it may concern:

Be it known that we, WALTER PEARSON and EDWIN P. QUATTLEBAUM, citizens of the United States, residing at Mobile, in the county of Mobile and State of Alabama, have invented certain new and useful Improvements in Locomotive Ash-Pans; and we do hereby declare the following to be a full, clear, and exact description of the invention, such as will enable others skilled in the art to which it appertains to make and use the same.

The present invention relates to improvements in locomotive ash pans, and has for an object to provide an improved ash pan from the bed of which ashes may be dumped without the necessity of stopping the locomotive.

It is another object of the present invention to provide an improved ash pan formed with an inclined bed for directing the ashes received from the grate to dump buckets, which may be operated by mechanism from the fireman's position in the locomotive cab.

A further object of the present invention resides in providing an improved ash pan of the above character which will be equipped with a device for introducing steam to the inclined pan bed for driving the ashes into the dump buckets, and with spray nozzles for supplying water to cool the ashes in the dump buckets prior to depositing on the roadbed.

Reference is had to the accompanying drawings, in which similar parts are indicated by similar reference symbols throughout the several views, and in which:

Figure 1 is a diagrammatic view of a locomotive equipped with an improved ash pan constructed in accordance with the present invention; Fig. 2 is an enlarged side elevational view of the ash pan, parts being shown in section; and Fig. 3 is a top plan view of the pan on the scale shown in Fig. 2.

Referring more particularly to the drawings, in Fig. 1 is designated in dotted lines a locomotive, the ash pit of which is formed with wire mesh walls 1, supported from the locomotive frame in any suitable manner, and which permit access of air and exit of dust and smoke without permitting live coals or large particles to escape.

The bed of the improved ash pan preferably consists of a pair of walls 2 and 3 joined centrally of the ash pit, and inclined

downwardly therefrom toward the rear and front of the locomotive, respectively. The walls 2 and 3 may be made in one piece from suitable material generally employed for this purpose, or the same may be constructed singly and subsequently united.

Longitudinal side sills or hangers 4 and 5 are connected to the locomotive framework, or to the ash pit walls 1, and serve to support the inclined walls 2 and 3, and said walls are advantageously joined at opposite ends by transverse beams 6 and 7.

From an inspection of Fig. 2 it will be apparent that the inclined walls 2 and 3, forming the bed of the improved ash pan, terminate short of the lower ends of the side sills 4 and 5, and in the space thus formed are arranged dump buckets 8 and 9, positioned angularly with respect to said inclined walls and designed to catch the ashes which descend by gravity thereto.

These dump buckets 8 and 9 are provided with trunnions 10 and 11, projecting from opposite sides of the same, as disclosed in Fig. 3, and fitted in the adjacent sills 4 and 5 for mounting the buckets for revolution in that manner indicated by dotted lines in Fig. 2. To the dump buckets are connected rods 12 and 13, curved at their outer ends to conform to the shape of the bucket bottoms, and connected for operation at their inner ends to levers 14 and 15, respectively, which are located for convenience of manipulation by the fireman from his position within the engine cab; or the same may be connected to other mechanism for connecting the dump buckets for simultaneous control.

In substantially the center of the ash pan is supported a steam jet 16, in communication with the steam dome or other source of supply through a connection 17, and having two branches for directing the issuing fluid against the ashes in the inclined bottom walls 2 and 3 and thereby driving the same into the dump buckets 8 and 9.

Spray heads 18 and 19 are supported in the improved ash pan above each of the dump buckets 8 and 9, and the same are in communication with a source of water supply through pipes 20 and 21, and the same serve to deliver water upon the hot ashes to thereby cool the same prior to depositing upon the roadbed.

In operation, the ashes descend from the

grate above to the improved ash pan and, falling upon the inclined walls 2 and 3 constituting the bed of the same, are thereby directed downward and into the dump buckets 8 and 9, which action is assisted by the steam issuing from the jet 16.

As soon as sufficient ashes have collected in the buckets 8 and 9, the fireman may turn on the water supply and sprinkle the 10 ashes from the heads 18 and 19 which will extinguish any live coals and cool the mass, so as to prevent the likelihood of the cross ties catching fire. The levers 14 and 15 may now be operated from the full line to the 15 dotted line position shown in Fig. 2, and the buckets 8 and 9 will be revolved about their pivots 10 and 11 and will deposit the ashes upon the roadbed without the necessity of stopping the locomotive, or of the 20 excessive raking now usually required of the fireman. The buckets are returned to position by a reverse movement of the levers 14 and 15 in readiness to receive subsequent 25 loads, and the operation may be repeated from time to time as necessity requires.

It is to be understood that the improved ash pan as above described may be made in suitable sizes and with slight variations of construction to fit various types of passenger and freight locomotives, and it is apparent that changes may be made in the construction, combinations and arrangement of parts without departing from the spirit of 30

our invention, provided such changes fall within the scope of the appended claim. 35

We claim:—

In a locomotive ash pan of the character described, the combination of mesh side walls, a bottom including a pair of inverted V-shaped hangers, a pair of diverging inclined bottom walls supported from said hangers and terminating at their lower ends short of the lower ends of said hangers to provide spaces therebetween, beams connecting the ends of said hangers above said 40 spaces, dump buckets, trunnions on said buckets journaled in the lower ends of said hangers and supporting said dump buckets angularly in said spaces and with their adjacent ends normally in contact with the 45 lower ends of the bottom walls for receiving the ashes therefrom, steam jets for driving the ashes down said inclined walls and into the buckets, water sprays above said dump buckets for extinguishing the live coals and 50 sparks therein, rods having curved outer ends conforming to the curvature of the bucket bottoms and connected to the latter, and means connected to the opposite ends of said rods for shifting the same to revolve and dump said buckets, substantially as described. 55

In testimony whereof, we affix our signatures.

WALTER PEARSON.

EDWIN P. QUATTLEBAUM.
